UNITED STATES PATENT OFFICE

JOHN L. LATTA, OF HICKORY, NORTH CAROLINA.

PUMP.

1,170,647.

Specification of Letters Patent.

Patented Feb. 8, 1916.

Application filed March 24, 1915. Serial No. 16,708.

To all whom it may concern:

Be it known that I, JOHN L. LATTA, a citizen of the United States, residing at Hickory, in the county of Catawba and State of North Carolina, have invented a new and useful Pump, of which the following is a specification.

The present invention appertains to pumps, and more particularly to pneumatic displacement pumps.

It is the object of the invention to provide a pneumatic displacement pump of novel and improved construction, adapted to be submerged in the water or other liquid which is to be elevated, and embodying novel features of construction to enhance the utility and efficiency of the structure, the present device being an improvement of the pump disclosed in my Patent No. 1,000,021, issued

August 8, 1911.

The cardinal feature of the invention resides in the provision of unique means for controlling the admission and discharge of the compressed air or other pressure fluid into and out of the twin or companion cylinders, whereby the water or liquid is forced by the air or pressure fluid from one cylinder, while the other cylinder is being filled by the water or fluid which flows thereinto by gravity.

It is also within the scope of the invention to improve the construction generally in its details, whereby the structure will operate in a most practical and effective manner.

With the foregoing and other objects which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the preferred embodiment in the accompanying drawings, wherein:

Figure 1 is a vertical or longitudinal section of the improved pump, the upper and lower end portions being moved out of alignment and placed side by side in order that the details may be illustrated on as large a scale as possible, it being understood that the right hand portion of Fig. 1 is a con-

tinuation of the lower end of the left hand portion of said figure. Fig. 2 is a fragmental side elevation of the pump, portions being broken away and shown in section. Fig. 3 is a cross section taken on the line 3-3 of Fig. 2.

In carrying out the present invention, there is provided a pair of parallel co-extensive vertical twin cylinders 1 and 2, to the upper ends of which is secured a common head 3 having an upstanding standard or portion 4. A common bottom 5 is secured to the lower ends of the cylinders 1 and 2, and is provided with water or fluid inlets 6 and 7 for the respective cylinders 1 and 2. The bottom 5 is provided with a depending enlargement 8 between the inlets or ports 6 and 7, and a pair of ducts or passages 9 extend from the respective cylinders 1 and 2, the ducts or passages 9 and 10 being provided within the bottom 5 and its enlargement 8 in any suitable manner.

The passages 9 and 10 are provided with the downwardly facing valve seats 11 and 12, against which the respective check or ball valves 13 and 14 seat upwardly under the influence of the respective springs 15 and 16. The springs 15 and 16 seat upon plugs 17 threaded or engaged into the lower ends of the passages 9 and 10. The enlargement or portion 8 is provided with a duct or passage 18 communicating with the passages 9 and 10 below or beyond the valves 13 and 14, respectively, and a pipe 19 has its lower end connected to the bottom 5 to communicate with the passage 18 and has its upper end connected to the head 3 to communicate with the lower end of a vertical or longitudinal bore or passage 20 provided in the head 3 and the upstanding portion 4 thereof. The water or fluid discharge pipe is adapted to be attached to the upper end of the portion 4 to communicate with the upper end of the passage 20, the said discharge or exhaust pipe not being illustrated, but the use thereof nevertheless is readily understood.

Check or clack valves 21 and 22 are disposed within the lower ends of the respective cylinders 1 and 2 and are seatable downwardly over the water inlets 6 and 7, the bottom 5 of the cylinders being provided with suitable guides 23 to guide the valves 21 and 22 and limit their upward movement when unseating. The check valves 21

60

75

85

100

105

and 22 allow the water to flow into the cylinders by gravity, but prevent the water and air from being discharged out of the cylinders through the inlets 6 and 7.

5 Disposed within the respective cylinders 1 and 2 are the vertical sleeves or tubular members 24 and 25 which are concentric with and spaced from the walls of the respective cylinders. The sleeves 24 and 25 10 are also shorter than the cylinders and have attached to their lower ends, the respective pistons 26 and 27 which work snugly within the respective cylinders 1 and 2. The pistons 27 have packings 28 engaging the walls 15 of the cylinders to prevent leakage between the pistons and cylinder walls. The pistons 26 and 27 have the respective central openings 29 and 30, and the respective valve seats 31 and 32 at the upper ends of the openings 20 29 and 30. The valve seats 31 and 32 face upwardly. The respective cylinders 1 and 2 are provided with apertures or openings 34 immediately above the valve seats 31 and 32, respectively. A buoyant ball valve 35 is 25 mounted loosely within the sleeve 24, and a similar valve 36 is mounted loosely within the sleeve 25, the valves 35 and 36 being seatable upon the seats 31 and 32, respectively, and provide check valves for the 30 lower ends of the respective sleeves.

A plug or cap 37 is secured to the upper end of each of the sleeves 24 and 25, and is provided with a recess 38 in which is seated a ball valve 39 which is spaced below the 35 mouth of the recess 38. The sleeves 24 and 25 are provided with the vent apertures 40 and 41 immediately below the plugs 37 to allow the water to flow properly into and out of the sleeves. The plugs 37 are provided with upstanding guides pins 42 which are slidable through the respective plates 43 and 44 disposed within the cylinders 1 and 2. Coiled wire expansion springs 45 surround the upper protruding portions of 40 the pins 42 and their lower ends seat upon the respective plates 43 and 44, while the upper ends of the springs 45 seat against nuts 46 secured upon the upper ends of the 45 guide pins 42. The springs 45 tend to raise the sleeves 24 and 25. The respective plates 43 and 44 are provided with depending nipples 47 and 48 having the lower valve seats 49 against which the ball valves 39 are 50 adapted to seat for closing the ducts or passages through the nipples. Pipes or tubes 50 and 51 disposed axially within the respective cylinders 1 and 2 have their lower ends secured to the respective plates 43 and 44 to communicate with the respective nipples 47 and 48, and the upper ends of the 55 pipes 50 are secured to the head 3.

The head 3 and its upstanding portion 4 are provided with ducts or passages 52 and 53 which have their lower ends communicating with the upper ends of the respective

pipes 50 and 51, and the passages 52 and 53 extend to and are in communication with a bore or chamber 54 provided in the upper end portion of the portion 4. The passage 52 communicates with the upper end of the 70 bore or chamber 54, while the passage 53 communicates with the lower end of the chamber 54.

Vertically elongated tray-shaped members 56 and 57 have their rims secured to the 75 opposite sides of the portion 4 in any suitable manner, and provide chambers 58 and 59 therein. The chamber 58 is the dead air chamber, while the chamber 59 is the live air chamber. The chamber 59 is supplied 80 with compressed air or pressure fluid by means of a pressure fluid pipe (not shown) engaged into a bore or socket 60 provided in the upper end of the portion 4 between the passage 20 and chamber 54, there being 85 a port or passage 61 between the bore 60 and upper end of the chamber 59. The dead or spent air is discharged from the upper end of the chamber 58 through a port or opening 62 provided in the upper end of the 90 member 56, and a suitable air discharge pipe (not shown) may be attached to the upper end of the member 56 to allow the air to pass upwardly to the atmosphere.

An air or pressure fluid controlling valve 95 63, which is of cylindrical formation, is journaled through the portion 4, so that its ends project into the chambers 58 and 59. The valve 63 is provided with an annular flange 64 at that side of the portion 4 nearest the chamber 59, and the flange 64 seats against a packing 65 embedded within the portion 4, to prevent the leakage of air from the live air chamber 59 into the dead air 100 chamber 58. That end portion of the valve 63 within the chamber 59 is provided with a pair of upper laterally spaced ports 66 and 67 within the chamber 59, and the opposite end portion of the valve 63 is provided with 105 a pair of upper laterally spaced ports 68 and 69 within the chamber 58. The valve 63 is provided with a passage 70 extending downwardly from the port 66 to the lower surface of the valve, and the opposite end portion of the valve 63 is provided with a passage 71 extending downwardly from the port 68 to the lower surface of the valve. Nipples 74 and 75 are secured to the end 110 portions of the valve 63 to communicate with the lower ends of the respective passages 70 and 71 and hose sections or flexible 115 conductors 76 and 77 have their upper ends engaged to the respective nipples 75 and 74. The lower ends of the flexible conductors 76 and 77 are engaged to the upstanding nipples 78 of members 79 attached to the opposite sides of the portion 4 within the lower 120 end portions of the members 56 and 57. The members 79 are provided with the respective ducts or passages 80 and 81 extending from 125

the flexible conductors 76 and 77 to ducts or passages 82 and 83, respectively, provided in the lower end of the portion 4 and the head 3. The passages 82 and 83 extend to the upper 5 ends of the respective cylinders 1 and 2 to allow the air to flow into and out of the cylinders properly.

Means are provided for closing the ports 56, 67, 68 and 69, and to this end pintles 84 10 are engaged to opposite sides of the portion 4 immediately above the valve 63, and fiber or other compressible disks 85 and 86 are mounted for rotation upon the pintles 84 within the respective chambers 58 and 59. 15 The disks 85 and 86 coöperate with the respective pairs of ports 68-69 and 66-67, and the disks are sufficiently compressible or yieldable to properly close the ports. That end portion of the valve 63 within the chamber 58 has its upper portion cut away, as at 20 86^a, so as to bring the portion 86^a having the ports 68 and 69 closer to the center of the valve. The portion 86^a has a larger radius of curvature than the cylindrical surface of 25 the valve, and the disk 85 bears upon the portion 86^a. Thus, when the valve 63 is in an intermediate or neutral position, both of the ports 68 and 69 will be closed by the disk 85.

30 The portion 4 is provided with an opening 87 between the chamber 54 and the bore 87^a in which the valve 63 is journaled, and the portion 4 is provided with a duct or passage 88 extending from the opening 87 to the 35 dead air chamber 58. The valve 63 is provided with a radially projecting finger 89 projecting through the opening 87 into the chamber 54 whereby the valve is adapted to be oscillated by the device within the chamber 54.

40 The valve operating device embodies a piston 90 mounted for vertical reciprocation within the chamber 54 and having a central or intermediate opening 91 receiving the finger 89, whereby when the piston 90 is reciprocated it will oscillate the valve 63 properly. The piston 90 has suitable packing means 92 above and below the opening 91 and engaging the walls of the chamber 54 to prevent leakage. The piston 90 is also provided with bores or passages 93 and 94 extending from the upper and lower ends, respectively, of the piston to the opening 91, and a stem 95 is slidable through the bores 45 or passages 93 and 94 and is provided at its ends with upper and lower valves 96 and 97, respectively, seatable against the respective ends of the piston. The upper end of the chamber 54 is normally closed by means of 50 a removable plug or cap 98 which permits access to be had to the chamber 54 when the parts are assembled, or separated. The valve 63 is provided with a diagonal passage 99 establishing communication between the 55 ports 66 and 69, and is provided with a sec-

ond diagonal passage 100 establishing communication between the ports 67 and 68.

In operation, supposing the cylinders 1 and 2 to be submerged in water, and the valve 63 is so set that the respective disks 75 85 and 86 cover and close the ports 68 and 66, with the ports 67 and 69 uncovered or open, the cylinders 1 and 2 would be brought into communication with the respective chambers 59 and 58. Thus, since the port 66 is closed, the live air cannot flow through the said port, and the upper end of the cylinder 2 will thus be brought into communication with the dead air chamber 58, since this communication is established by the 80 passage 83, passage 81, flexible conductor 77, passage 70, passage 99 and port 69 which is uncovered within the dead air chamber 58. The cylinder 1 is in communication with the live air chamber 59, in view of the fact that the port 67 is uncovered and allows the air to flow through the passage 100 into the passage 71, and since the port 68 is closed, the air will be compelled to flow downwardly through the passage 71, flexible conductor 76, passage 80, and passage 82 into the upper 90 end of the cylinder 1. For the reason that the upper end of the cylinder 2 is in communication with the dead air chamber 58, the air may readily flow from the cylinder 2 into the chamber 58 and thence to the atmosphere, and the water may enter the lower end of the cylinder 2 through the inlet 7, the valve 22 being unseated by the inflowing water, and the water passing upwardly through the opening 30 of the piston 27 to fill the cylinder 2. Due to the fact that the cylinder 2 is relieved of air pressure, the sleeve 25 will be raised under the influence of the springs 45 so that the respective valve 39 will seat against the nipple 48 for closing the passage through the nipple and pipe 51. Consequently the cylinder 2 may be readily filled by water which flows into the cylinder by gravity, and the sleeve 25 will also be filled with water since the vent aperture 41 allows the air to escape from the sleeve 25, and the buoyant ball valve 36 will rise to the upper end of the sleeve 25 when the sleeve becomes filled with water. The openings 34 allow the water to flow therethrough from the lower portion of the sleeve 25 into the cylinder above the piston 27. The cylinder 1 which was previously filled with water, in the manner that the cylinder 2 has just been described as being filled with water, is emptied, since the water therein is forced outwardly or displaced by the air or pressure fluid. Thus, supposing the cylinder 1 to be full of 100 water with the sleeve 24 raised to seat the respective valve 39, and with the valve 35 raised to the upper end of the sleeve 24, the air will enter the cylinder 1 to displace the water. The air will flow from the live air

105

110

115

120

125

130

chamber 59 through the port 67, passage 100, passage 71, flexible conductor 76, passage 80, and passage 82 into the cylinder 1, and the air in entering the cylinder 1 will 5 force the water downwardly through the passage 9, and the valve 13 will be unseated by the pressure of the water to allow the water to flow through the passage 18, pipe 19 and passage 20 to the outlet or discharge 10 pipe. The valve 21 will seat under the pressure of water and air, and as the water level lowers within the cylinder 1, and in the sleeve 24, the valve 35 will lower therewith, the vent aperture 40 permitting the 15 water to flow out of the sleeve 24. The water flows from within the cylinder 1 through the openings 33 and opening 29 to the passage 9, and when the water above the openings 33 is all discharged, the valve 35 will 20 seat upon the seat 31 to close the opening 29, and this will prevent the escape of air from the cylinder 1 through the opening 29 and passage 9. Furthermore, the passage through the piston 26 being closed, causes 25 the compressed air within the cylinder 1 to force the piston 26 downwardly, and this will carry the sleeve 24 downwardly to unseat the respective valve 39, and the air may then escape up through the nipple 47, pipe 30 50, and passage 52 into the upper end of the chamber 54. The air in entering the upper end of the chamber 54 will seat the upper valve 96 of the piston 90 to close the upper passage 93, and the piston 90 will 35 then be forced downwardly within the chamber 54 so as to swing the finger 89 downwardly and swing the valve 63 to its opposite position. The valve 96 being seated will unseat the lower valve 97, and allow 40 the air to escape from the lower portion of the chamber 54 through the passage 94, opening 91, opening 87, and passage 88 into the dead air chamber 58, and thence to the atmosphere. 45 Due to the fact that the valve 63 is reversed, in the manner just indicated, the port 68 will be uncovered and the port 69 will be covered, while the port 66 will be uncovered and the port 67 will be covered. 50 This will reverse the operation, since the cylinders 1 and 2 are now brought into communication with the dead air and live air chambers, respectively. Thus, the port 66 being uncovered will allow the air to flow 55 therethrough, the port 69 in being covered preventing the air from passing into the dead air chamber 58 and constraining the air to pass downwardly through the passage 70, flexible connection 77, and passages 81 60 and 83 into the cylinder 2 to displace the water therefrom in the manner that the water was displaced from the cylinder 1. The port 68 being uncovered, and the port 67 being covered, brings the cylinder 1 in communication with the dead air chamber 58, 65 since the air is allowed to pass from the cylinder 1 through the passage 82, passage 80, flexible conductor 76, passage 71 and port 68 into the chamber 58. The water is thus allowed to flow by gravity into the cylinder 1, and the water within the cylinder 2 will be forced out through the passage 10 into the passage 18, thence up through the pipe 19 and passage 20. Since the operation is just the reverse of the operation above 70 described, a reiteration is not deemed necessary, it being evident that when the water is discharged from the cylinder 2, the valve 36 will be seated over the opening 30 to move the piston 27 and sleeve 25 downwardly so as to open the passage through the nipple 48 to allow the air to flow through the pipe 51 and passage 53 into the lower end of the chamber 54, which will cause the piston 90 to move upwardly within the chamber 54 for reversing the valve 63 to its original position, the valve 97 being seated and the valve 96 unseated for allowing the air to escape from the upper portion of the chamber 54 through the passage 93, opening 91, opening 87 and passage 88 to the dead air chamber 58. The twin cylinders are thus alternately filled and emptied automatically, whereby the water is raised in a practically continuous stream. The valves 13 and 14 prevent 90 the retrograde movement of the water back into the cylinders from the water outlet passage, and the check valves 21 and 22 prevent the accidental discharge of the water from the lower ends of the cylinders through 100 the inlets 6 and 7. The valves 39 are only unseated for an instant, during the reversing of the valve 63, and are immediately seated by the springs 45, after the valve 63 is reversed. The flexible tubes or conductors 76 and 77 permit the valve 63 to oscillate without interrupting the flow of air between the valve 63 and the cylinders, and the ports 68 and 69 are arranged to both be 105 closed when the valve 63 is at an intermediate position. This will prevent the live air from escaping from the chamber 59 through the valve 63 into the chamber 58, during the time that the valve is being reversed. The sleeves 24 and 25 provide guides for the 110 valves 35 and 36, respectively, and also serve to carry the valves 39 for controlling the admission of air into the inlet ends of the passages communicating with the ends of the chamber 54. The parts 3, 4, 56 and 57 also 115 provide a body or frame for the parts carried thereby, as will be apparent. 120 Having thus described the invention, what is claimed as new is:

1. The combination in a pneumatic pump, 125 a cylinder, an air outlet passage, a piston working within the cylinder and having an opening, a guide carried by the piston, a buoyant valve guided by said guide and seatable over the opening of the piston, a 130

valve carried by the guide for closing the air outlet passage, and means for yieldingly moving the guide to seat the last mentioned valve.

5. 2. The combination in a pneumatic pump, a cylinder having an air outlet passage, a piston movable within the cylinder and having an opening, a buoyant valve seatable over said opening, a second valve connected 10 to the piston to be moved therewith and operable for closing said passage, and means for yieldably moving the piston to cause the last mentioned valve to normally close said passage.

15. 3. The combination in a pneumatic pump, a cylinder, a depending nipple therein providing an air outlet for the cylinder, a spring pressed member movable within the cylinder and having a valve at one end seatable against the nipple to normally close the passage therethrough, a piston attached to said member and movable snugly within the cylinder, the piston having an opening, and a buoyant valve guided by said member and 20 seatable over the opening of the piston.

25. 4. The combination in a pneumatic pump, a vertical cylinder, a depending air outlet pipe therein, a plate attached to the lower end of said pipe and having a depending nipple in communication with said pipe and provided with a valve seat, a vertically movable member within the cylinder having portions slidable through said plate, springs between said portions 30 and plate for normally raising said member, said member having a valve at its upper end to seat against said nipple, a piston attached to said member and working snugly within the cylinder, the piston having an opening, and buoyant valve guided by said member and seatable over the opening of the piston.

40. 5. The combination in a pneumatic pump, a vertical cylinder, having an air outlet passage, a sleeve movable vertically within the cylinder and having openings for the passage of water therethrough, a piston secured to the lower end of the sleeve and working snugly within the cylinder, the piston having an opening, a buoyant valve mounted within the sleeve and seatable over 45 said opening of the piston, a valve carried by the upper end of the sleeve and arranged to close said passage, and means for yieldingly raising the sleeve.

55. 6. The combination in a pneumatic pump, a vertical cylinder, a depending air outlet pipe within the cylinder, a member carried by the lower end of said pipe and having a valve seat, a vertically movable sleeve within the cylinder, the upper end of the sleeve having means engaging said member to guide the sleeve, spring means between said means and said member, for yieldingly raising the sleeve, a valve car-

ried by the upper of the sleeve to seat against said seat, a piston movable snugly within the cylinder and attached to the lower end of the sleeve, the sleeve having openings therein for the passage of water therethrough, the piston having a central opening, and a buoyant valve movable within the sleeve and seatable over the opening of the piston.

7. The combination in a pneumatic pump, a pair of vertical cylinders, a body attached to the upper ends thereof and having live and dead air chambers, an oscillatory valve journaled within the body and projecting within said chambers, the valve having a pair of ports within each chamber, a passage connecting one port of one pair and one port of another pair, a passage connecting the other ports of the two pairs, and a passage extending from one port of each pair, a flexible conductor connected to the last mentioned passage of each pair of ports, the body having passages communicating with the upper ends of the cylinders and to which the flexible conductors are connected, means within said chambers and coöperating with the ports whereby when the valve is oscillated, the ports will be alternately covered and uncovered for alternately establishing communication between the cylinders and live and dead air chambers, and means for oscillating the valve.

8. The combination in a pneumatic pump, a pair of vertical cylinders, a body attached to the upper ends thereof and having live and dead air chambers, an oscillatory valve journaled within the body and projecting within said chambers, the valve having a pair of ports within each chamber, 100 a passage connecting one port of one pair and one port of another pair, a passage connecting the other ports of the two pairs, and a passage extending from one port of each pair, a flexible conductor connected to the last mentioned passage of each pair of ports, the body having passages communicating with the upper ends of the cylinders and to which the flexible conductors are connected, rotatable disks within said 105 chambers and bearing against said valve to cover and uncover the respective ports when the valve is oscillated, and whereby the cylinders are alternately brought into communication with the live and dead air chambers, and means for oscillating the valve.

9. The combination in a pneumatic pump, a pair of vertical cylinders, a head secured to the upper ends thereof and having an 110 standing portion, tray-shaped members having their rims secured to opposite sides of said portion and providing live and dead air chambers, a cylindrical valve journaled through said portion and projecting into 115

120

125

130

- said chambers, the valve having a pair of ports within each chamber, a passage between one port of one pair and one port of another pair, and a passage between the 5 other ports of the two pairs, a flexible conductor connected to one port of each pair, the head and said portion having a pair of passages communicating with the upper ends of the cylinders and to which the said 10 flexible conductors are connected, means for oscillating the valve, and members carried by the opposite sides of said portion and coöperating with said ports for covering and uncovering them, whereby the cylinders 15 are alternately brought into communication with the live and dead air chambers when the valve is oscillated.
10. The combination in a pneumatic pump, a pair of vertical cylinders, a head 20 secured to the upper ends thereof and having an upstanding portion, tray-shaped members having their rims secured to opposite sides of said portion and providing live and dead air chambers, a cylindrical valve 25 journalled through said portion and projecting into said chambers, the valve having a pair of ports within each chamber, a passage between one port of one pair and one port of another pair, and a passage between 30 the other ports of the two pairs, a flexible conductor connected to one port of each pair, the head and said portion having a pair of passages communicating with the upper ends of the cylinders and to which 35 said flexible conductors are connected, means for oscillating the valve, pintles carried by the opposite sides of the said portion within said chambers, and rotary disks mounted upon said pintles and bearing 40 against the valve for covering and uncovering the respective ports, whereby the cylinders are alternately brought into communication with the live and dead air chambers when the valve is oscillated.
- 45 11. The combination in a pneumatic pump, a body having a chamber and air passages communicating with the opposite ends thereof, a reversible valve device carried by the body, a piston movable within 50 said chamber and operatively connected to said valve device, the piston having an opening between its ends, the body having an outlet passage communicating with said opening, the piston having passages ex-
- tending from its ends to said opening, a 55 stem extending slidably through said passages of the piston and having valves at its ends seatable against the ends of the piston whereby when one valve is seated the other will be unseated.
- 60
12. The combination in a pneumatic pump, a pair of vertical cylinders, a body secured to the upper ends thereof and having live and dead air chambers and a third chamber, an oscillatory valve journalled 65 within the body and projecting within the live and dead air chambers, the valve having a pair of ports within each of the live and dead air chambers, a passage between one port of one pair and one port of the 70 other pair, and a passage between the other ports of the two pairs, a flexible conductor connected to one port of each pair, the body having a pair of passages communicating with the upper ends of the cylinders and to 75 which the respective flexible conductors are connected, members within the live and dead air chambers and coöperating with said ports to cover and uncover the same when the valve is oscillated, whereby the cylinders 80 will be alternately brought into communication with the live and dead air chambers, the body having passages establishing communication between the ends of the third chamber and the respective cylinders, means 85 for closing the last mentioned passages when the cylinders are filled with liquid and for opening said passages when the cylinders are emptied, the body having an opening between the third chamber and valve, the 90 valve having a finger projecting through said opening, a piston slidable within the third chamber and having an opening between its ends receiving said finger, the body having an air outlet passage communicating with the opening of the piston, the 95 piston having passages extending from its ends to the opening thereof, and a valve stem slidable through the passages of the piston and having terminal valves seatable 100 against the ends of the piston.

In testimony that I claim the foregoing as my own, I have hereunto affixed my signature in the presence of two witnesses.

JOHN L. LATTA.
